UNITED STATES PATENT OFFICE.

LOUIS CARROLL STUKENBORG, OF CHICAGO, ILLINOIS, ASSIGNOR, BY MESNE ASSIGNMENTS, TO STUKENBORG CORPORATION, OF WILMINGTON, DELAWARE, A CORPORATION OF DELAWARE.

COTTON PICKER.

Application filed October 27, 1920. Serial No. 419,976.

To all whom it may concern:

Be it known that I, LOUIS CARROLL STUKENBORG, a citizen of the United States, and a resident of Chicago, in the county of Cook and State of Illinois, have invented certain new and useful Improvements in Cotton Pickers; and I do hereby declare that the following is a full, clear, and exact description thereof, reference being had to the accompanying drawings, and to the characters of reference marked thereon, which form a part of this specification.

This invention relates to improvements in cotton harvesting machines, and refers more particularly to novel picker mechanism for removing the cotton directly from the boll, or alternately removing cotton from any mass and discharging it by vacuum or otherwise to a place of disposal.

Among the objects of the invention is to simplify the picker mechanism of a cotton picking machine, reduce the cost of its construction, reduce the weight of the picker mechanism, reduce the power to drive the mechanism, and to otherwise improve picker mechanisms.

A cotton picker mechanism embodying my invention embraces interacting brush means which may, and as herein shown, have the form of rotary brushes that rotate on axes parallel to each other and are adapted for direct contact with the cotton which is being picked or handled to draw it into a frame or head which surrounds the picker mechanism in a manner to furnish a conduit for the passage of the cotton rearwardly between and away from the brush means and to enclose said mechanism and support suitable bearings for the movable parts thereof, together with means co-operating with the brush means for clearing the brush means of the cotton and for depositing the cotton cleared from the brush means to means for carrying the cotton rearwardly to the place where it is deposited, as, for instance, depositing it into a movable column of air which is maintained by connection of the head with a suction device.

The present invention relates more particularly to the means for clearing the cotton fiber from the brush means to guards and to the combination of said clearing means and guards with the brush means and with other elements which go to make up a complete picker mechanism.

The invention consists in the combination and arrangement of the parts shown in the drawing and described in the specification, and is pointed out in the appended claims.

In the drawing:

Figure 1 is an axial section of a picker head and mechanism embodying my invention, the section being taken at right angles to the rotative brushes.

Figure 2 is a front elevation thereof.

Figure 3 is a side view of the casing or head showing the arrangement of the gears for driving the brush means.

Figure 4 is a view similar to Figure 1, showing a modification of the clearing means.

Figure 5 is a further modification showing another form of brush means.

Referring first to Figures 1 to 3, inclusive, 10, 10 designate as a whole the brush means which have the form of rotating cores 11, 11 that are fixed on shafts 12, 12 which extend transversely of the head, or casing, designated as a whole by 13, and more specifically hereinafter described. The said brush means embraces also, as shown in the last mentioned figures, bristle tufts 14 that are fixed to and extend radially from the cores and are adapted to interact in such a way that when in contact with the cotton and rotated in the direction indicated by the arrows in Figure 1, draw the cotton rearwardly between the brushes into the casing or head.

The said casing or head, as shown, is made of two generally similar hollow parts 16, 17 that may be made of cast metal or sheet metal suitably formed. Said casing parts are generally symmetrical with respect to each other, except for an extension 18 at one side of the head to receive the

driving gears for the brush means herein-after described. Said gearing extension or housing is closed by a cover plate 19. The two parts of the head casing may be joined 5 in any suitable manner as by means of overlapping lugs 20 which are pierced for the passage of screws or bolts 21. The formation of the two parts of the casing members is such that, when assembled, there is 10 produced at the front part a mouth portion 22 in which the brushes 10 are rotatively mounted, and a neck portion 23 which is adapted for connection with a conveyor tube 24, which itself is adapted for connection 15 to a suction fan, or other means for inducing a rearwardly flowing current of air through the head and conveyor tube. In the present instance a portion of the induced air enters the casing or head through the 20 mouth 22, but the major portion of the air enters the head through openings 25 that are formed in the head. There may be one or more of such openings and the area of the single or multiple openings will depend 25 upon conditions of work such, for instance, as the staple of the cotton, the volume of the cotton passing through the head in a given time, the air current inducing power, etc.

The shafts 12 on which the brush cores are 30 directly mounted are herein shown as of square cross sections to enter corresponding openings in the cores. The ends of the shafts are turned to form cylindric bearing portions 27 which are supported on opposing 35 side walls 28 of the head through the medium of suitable roller bearings designated as a whole by 29 that are themselves supported in inwardly extending socketed members 30 which may be made integral with or 40 attached in any suitable manner to the casing walls. The brush cores are provided with endwise extended enlargements or shells 31, which, when the cores are made of wood, are fitted over the ends of the cores, 45 and, when made of metal, can be integral extensions of the metal cores. These shells overlap the socketed members 30 in the manner best shown in Figure 2 almost to the adjacent side walls of the head, and are made 50 internally larger than the external diameter of the socketed members, so as to prevent winding of the cotton about the bearings.

The brush cores extend beyond one of the side walls 28 of the casing, at the mouth 55 thereof, and intermeshing gears 32, 32 are fixed to those corresponding ends of the shaft that so project exteriorly from the casing. To one of the shafts, or, it may be to one of the gears, is fixed a worm gear 33 that 60 meshes with a worm 34 which is fixed to a shaft 35, that is mounted in suitable bearings 36 carried by the casing. The said shaft 35 extends rearwardly for connection to suitable driving power, as, for instance, 65 an electric or other motor, supported on the

head, or a motor supported rearwardly of the head by suitable driving connections.

38, 38 designate guards which are attached to opposite walls 39 of the casing head adjacent the walls 30. Said guards extend inwardly toward each other across the front faces of the brushes. They thus extend transversely with respect to the axes of the brush cores and are, preferably, so located that the active members or bristles 14 of the 75 brushes extend forwardly beyond and between them in the manner indicated in Figure 1. The number of such guards will depend upon the number of the active brush elements employed. In the arrangement 80 shown there are four guards extending across each brush, and with this arrangement two adjacent guards can readily be made of a single hair-pin shaped piece of wire attached at its closed portion to the 85 casing wall 39 by means of a bolt 41. The foregoing constitutes a convenient means of attachment of the guards to the head casing, but each two guards thus composed of a single piece of wire will be hereinafter referred 90 to in the singular.

The guards shown in Figures 1 and 2 are curved inwardly at 45 and are thence directed rearwardly between the brushes to constitute clearer and guide extensions 46. 95 The terminals of said extensions are, preferably, of such length as to extend reasonably beyond the circumferential lines defining the peripheries of the active brush elements.

In the construction shown in Figure 1, a set of guards that spring from one wall 39, extend at their curved portions 45 beyond and across the corresponding curved portions of the guards that spring from the opposite wall, so that thereby the guide and clearer terminals of the guards lie one across the other, with the clearer extensions 46 forming integral parts of the guards 38 that spring from one wall 39 located closer 105 to the core of the brush 10 adjacent to the other wall 39 than to the brush that lies close to the wall 39 from which the guards spring.

In the construction shown in Figure 4, the 110 guards thereon, designated by 47 can be attached to the head or casing walls 39 in the same manner as before described, and are turned inwardly at 48 beyond the peripheries of the brush cores much in the same 115 manner as in the construction shown in Figures 1 and 2. However, the said guards from one wall of the casing or head do not extend beyond and across those which spring from the other wall 39 of the head. Said 120 guards have clearer extensions 50 which are joined to the guards by the curved portions 48, and which clearer extensions lie parallel 125 with respect to each other between the brush cores and extend through the active brush 130

elements. In both the constructions the combined guards and clearer means are flexible so as to permit them to move toward and from each other and thereby continuously move in the brush means in a manner to set up vibration to prevent the cotton fibre from clinging to the brush means.

The combined guards and clearer extensions perform two functions, and so far as 10 the specific structure is concerned, they may or may not be severally made of the same piece of wire or other material. It is convenient, however, to so form them and this construction is recommended.

15 The function of the rearwardly turned clearer extensions is to remove or comb the cotton fiber from the active elements of the brush, and this function is effected by reason of the fact that the bunches of cotton fiber picked from the cotton plant or from a mass of cotton, and drawn rearwardly between the active elements of the brush, spread the terminals of the clearer extensions. When the bunches of cotton fiber are 20 released from the clearer extensions, said extensions resume their normal positions, and this repeated spreading and restoring movement of the clearer extensions has the effect of vibrating said extensions so that said extensions serve, not only to remove the cotton from the active brush elements, but also by reason of their vibration to free the cotton from said extensions so that it will be passed or deposited in the current of air induced 25 rearwardly through the casing. The incoming bolls or bunches of cotton drawn rearwardly between the brushes and between the clearer extensions will have the effect to push a boll or bunch of cotton, ahead of it, in the event the latter should tend to cling thereto, this in addition to the vibratory action 30 of the clearer extensions.

The vibrational activity of the crossed extensions shown in Figure 1 will be greater 45 than that of the parallel clearer extensions shown in Figure 4. For this reason, the construction shown in said Figure 1 is thought to be more efficient, but it has been demonstrated that the construction shown 50 in Figure 4 is fully efficient to effect the functions described. It will also be observed that the cotton passing between the brushes is in most part between the clearer extensions and that while the ends of the tufts exert good traction pull on the cotton, the clearer extensions avoid as deep penetration 55 of the brushes in the cotton as would otherwise occur.

An advantage of making the clearer extensions (46, 50) continuous with or integral 60 parts of the guards (38, 47) is found in the simplicity of the construction and the manner of attaching the dual function devices to the casing. Furthermore, an advantage of

extending the guards inwardly between the 65 brushes is to avoid the entanglement of guard ends, which stop at the front of the brush means, with the hulls of the cotton, when picking from the plant, which may occur if the guards terminate short of each 70 other such distance that a hull or pod may enter between them. In the latter instance, the act of removing the hull or pod may tend to deform the guard. In the construction shown, however, this contingency does 75 not occur.

The construction shown in Figure 5 is in all essential respects the same as that shown in Figures 1 and 2, with the exception that 80 the brush means comprise, in addition to the cores 51, another form of active brush element. The said active brush elements consist, in this instance, of more or less solid projections 52 which are fixed to the periphery of the cores in any suitable manner. For instance, said extensions may be made of rubber, or other relatively resilient composition, and integral with sleeves 53 which surround and fit closely on the cores. Said sleeves may possess sufficient resiliency 85 to hold themselves on the cores, or it may be desirable to provide them with inwardly extending lugs 55 that engage suitably spaced recesses in the periphery of the core. 90

I claim as my invention:

1. Cotton picker mechanism embracing coacting rotative brush means, a casing enclosing said brush means and formed at one end with a mouth to receive the brush means and adapted for connection with suction means, and flexible vibratory guard and brush combing members extending between said brush means and terminating free-ended rearwardly beyond the plane of the axes of rotation of the brush means. 95

2. Cotton picker mechanism embracing coacting brush means, a casing enclosing said brush means and formed at one end with a mouth to receive the brush means and adapted for connection with suction means, and vibratory guide and brush combing members extending between said brush means and terminating rearwardly therebeyond, said members being crossed adjacent the front of the brush means. 100

3. A cotton picker comprising a casing having at one end a mouth formation and adapted for connection in rear thereof to suction means, coacting brush means mounted in the casing at said mouth formation and combined guards and brush combing means, the guards extending across the front of the brushes and the combing means being flexible and extending rearwardly between and terminating free-ended and vibrating 110 in rear of the brush means. 115

4. A cotton picker comprising a casing having at one end a mouth formation and

- adapted for connection in rear thereof to suction means, coacting brush means mounted in the casing at said mouth, and combined guards and flexible and vibratory brush clearer and guiding means extending in part across the front of the brush means and in part rearwardly between the brush means and free ended at their terminals in rear of the brush means.
10. 5. A cotton picker comprising a casing having at one end a mouth formation and adapted for connection in rear thereof to suction means, coacting brush means mounted in the casing at said mouth, and combined guards and vibrating brush clearer and guiding means extending in part across the front of the brush means and in part rearwardly between the brush means and free at their terminals in rear of the brush means, the clearer and guiding means being crossed adjacent the front of said brush means.
6. A cotton picker comprising a casing having at one end a mouth formation and adapted for connection in rear thereof to suction means, coacting brush means mounted in the casing at said mouth, and combined guards and brush combing and guiding means, the guards extending across the front of the brush means, and the combing and guiding means extending between the brush means and being vibratory and terminating in rear thereof, said casing being provided in rear of the brush means with an air inlet opening.
7. Cotton picker mechanism embracing coacting, rotative brush means, a casing enclosing and supporting them and having at one end a mouth formation and adapted for connection to suction means, and guards attached to opposing casing walls and extending across the brush means and turned rearwardly at their proximate ends to form flexible vibratory combing and guiding terminals which extend between the brush means and terminate freely in rear thereof.
8. Cotton picker mechanism embracing brush means, a casing enclosing and supporting them and having at one end a mouth formation and adapted for connection to suction means, and guards attached to the casing wall and extending across the brush means and turned rearwardly at their proximate ends to form resilient combing and guiding means that terminate in rear of the brush means.
9. Cotton picker mechanism embracing coacting, rotative brush means, a casing enclosing and supporting said brush means and having at one end a mouth formation to receive said brush means and adapted for connection in rear of said brush means to suction means, and flexible, vibratory cotton clearer wires extending between the brushes and free at their rear ends rearwardly beyond the axes of rotation of said brushes.
10. In combination with rotative, coacting brush means and the enclosing and supporting casing thereof, of flexible resilient strand-like clearer and guide members extending between the brush means and terminating free ended in rear of the brush means.
11. In combination with rotative, coacting brush means and the enclosing and supporting casing thereof, of resilient strand-like clearer and guide members extending between the brush means and terminating free ended in rear of the brush means, said members being crossed upon each other adjacent to the front of the brush means.
12. In combination with rotative, coacting brush means and the enclosing and supporting casing thereof, of flexible resilient strand-like clearer and guide members extending between the brush means and terminating free ended in rear of the brush means, and guard members integral with the clearer and guide members and curved outwardly away from the meeting plane of the brush means, across said brush means, and fastened to opposing walls of the casing.
13. In combination with the rotative, coacting brushes of a cotton picker mechanism, of flexible resilient, strand-like clearer and guide members extending between the brushes and having free ended terminals that extend rearwardly beyond the axes of rotation of the brushes.
14. In combination with the rotative, coacting brushes of a cotton picker mechanism, of resilient strand-like clearer and guide members extending between the brushes and having free ended terminals that extend inwardly beyond the brushes, said clearer and guide members being crossed upon each other at the front of the brushes.
15. A cotton picker comprising a casing having at one end a mouth formation and adapted for connection in rear thereof to suction means, coacting brush means within said mouth formation, and resilient strand-like cotton guiding and clearer members between the brushes and terminating free ended in rear of the brushes, said brushes having driving shafts, with intermeshing driving gears fixed on corresponding ends of said shafts, a worm gear fixed on one of said shafts, and a power shaft provided with a worm meshing with said worm gear.
16. In combination with the rotative, coacting brushes of a cotton picker mechanism, of strand-like, resilient guide means extending between the brushes and free

ended rearwardly beyond the plane of the centers of the brushes and yieldable toward and from the brushes.

17. In combination with the rotative, co-⁵acting brushes of a cotton picker mechanism, of flexible resilient guide means extending between the brushes and rearwardly free ended, said guide means limiting pene-

tration of the brushes in the cotton while permitting pulling engagement of the cotton with the brushes. ¹⁰

In witness whereof I claim the foregoing as my invention, I hereunto append my signature this twelfth day of October, 1920.

LOUIS CARROLL STUKENBORG.
